[57] CLAIM

The ornamental design for a sports glove, as shown and described.

DESCRIPTION

FIG. 1 is a top perspective view of a sports glove showing my new design in an operative position, the hand shown in broken lines is shown for illustrative purposes only and forms no part of the claimed design; FIG. 2 is a top perspective view thereof with the wrist wrap portion in an extended position;

FIG. 3 is a bottom perspective view thereof with the wrist wrap shown in an extended position;

FIG. 4 is a top perspective view of a second embodiment thereof;

FIG. 5 is a top perspective view thereof with the wrist wrap portion in an extended position; and,

FIG. 6 is a bottom perspective view thereof with the wrist wrap shown in an extended position.

The crosshatch shading shown in FIGS. 1-6 is understood to repeat throughout the indicated area.

*Fig. 1**Fig. 2**Fig. 3**Fig. 4**Fig. 5**Fig. 6*
